UNITED STATES PATENT OFFICE.

HANS HASS, OF HAMBURG-BERGEDORF, GERMANY.

SHIP'S FUNNEL.

Application filed December 31, 1924, Serial No. 759,189, and in Germany January 2, 1924.

In ships the funnel is mounted on the chimney hood, which is arranged in front of the boiler, and rises more or less above the boiler according to the size of the ship.

5 The effort of the designer has hitherto been to provide either uniform or if possible increasing cross-sectional areas for the flue gases from the lower end of the chimney-hood right up to the upper edge of the funnel. Any sort of narrowing of the cross-sectional area of the funnel was always avoided, because a deterioration of the draught was feared as a result of such narrowing.

10 15 Now this invention consists in the arrangement of a constriction in the funnels of ships, because experiments have yielded the surprising result that a strong constriction of the funnel arranged in a particular way causes not only no deterioration but actually an improvement of the draught, and moreover the constriction according to the invention very favourably affects the action of a special induced-draught device.

20 25 The subject matter of the invention is illustrated by way of example in the accompanying drawing, wherein:—

Fig. 1 is a longitudinal section of a constructional form of applicant's invention.

30 Figure 2 is a cross section on the line II—II in Figure 1.

According to the invention a boiler 1 is provided in a known manner with a chimney cowl 2 passing gradually into polygonal or round form at the top. On this chimney cowl is mounted in a known manner the cylindrical funnel 3. According to the invention the chimney hood 2 does not pass directly into the cylindrical funnel 3, but at this point is arranged an insertion 4, which consists of a double conical tube and occasions a considerable constriction 5 of the space inside the funnel.

40 45 The double cone tube is so shaped that the lower, comparatively short cone exhibits the form of a steep conical jacket, while the upper cone passes over more gradually into the cylindrical cross section of the funnel 3.

50 55 In the immediate neighborhood of the point of constriction 5 is further arranged an insertion 6, extending over the entire fun-

nel. This insertion may be located either entirely in the compass of the funnel 3 or in the compass of the chimney hood 2 or with one part in the funnel 3 and with the other 55 part in the chimney hood 2.

It is essential that its form should be that of a stream-line body, so that the flue gases can flow past it well without forming eddies. Notwithstanding this insertion 6 the cross 60 sections in the lower cone tube are so constructed that they form a stream tube with constantly decreasing cross-sectional area, and consequently the insertion requisite for the housing of the driving engine for the 65 flue-gas propeller or fan forms little or no obstruction.

Now experiments have shown that by such an arrangement of the constriction 5 and of the insertion 6 the natural draught of the 70 funnel is enhanced to a certain extent, for example from 3.5 millimetres' column of water to 5 millimetres' column of water. Now this increased natural draught can be still further improved by inserting a preferably two-vaned flue-gas fan 7, which is arranged at the point of constriction 5, the driving engine 8 being housed in the insertion 6. In consequence of the powerful constriction only a comparatively small flue-gas 80 fan is required, which again has the advantage that the same can be driven by a driving engine of comparatively low power, for example a steam turbine 9 with a comparatively high velocity, so that this driving 85 engine can also easily find room in the small insertion 6.

A substantial rise in the efficiency of the flue-gas fan 7 is obtained by mounting on the top of the insertion 6 a hub 10 with a 90 few vanes 11, only two or three for example.

The vanes 11 are directed oppositely to the direction of rotation 12 of the flue-gas fans 7, and do not extend over the entire diameter of the insertion 4 at this point but 95 are kept substantially shorter. By this means the result is obtained that when the flue-gas screw is working the current of flue-gas travelling along the walls of the insertion 6 received a twist opposite in direction 100 to the rotation of the flue-gas screw, and consequently leaves the flue-gas screw in a di-

rection parallel to the axis of the funnel, whereby the thrust exerted by the flue gas-screw on the current of flue gas is increased.

At the same time, however, the flow of the flue gases through the point of constriction is not materially retarded by the short guide blades when the flue-gas screw is not working.

To facilitate inspection of the flue-gas fan 10 and of the guide vanes 11, apertures 13 and 14 are preferably provided both in the insertion 4 and in the funnel 3, these apertures being normally closed by removable covers 15 and 16. In this manner it is possible to 15 inspect the flue-gas fan 7 and the guide vanes 11 at any time and to take them out of the funnel for the purpose of cleaning or dismantling.

The insertion 6 is furthermore so strongly 20 constructed that it can be utilized as a foundation for the support of the flue-gas fan and the turbine. This is made possible by virtue of the small dimensions and of the resulting slight weight of the flue-gas fan 25 and of the driving engine (steam-turbine).

From this construction there results the great advantage that a special foundation connected with the ship's hull is superfluous. As the parts of the funnel vary in length 30 owing to heating the driving engine shares the movements of these parts and thus maintains its relative position in the funnel. The clearance between the flue-gas fan and the chimney hood can on this account be reduced, 35 whereby the efficiency of the flue-gas fan is materially improved.

The invention is illustrated on the funnel of a single boiler. Obviously however the same can also be employed for the funnel of a plurality of boilers, wherein the chimney hoods of the individual boilers are carried into the funnel by a common intermediate piece.

What I claim is:—

45 1. A ship's smoke stack, comprising a substantially cylindrical funnel; a double conical insert in and connected with the said funnel to form a constricted passage therein, the diameter of said passage being substantially less than that of said funnel; a stream-line member in the funnel mounted underneath the point of constriction and exhibiting even, eddy-preventing guide surfaces, a propeller mounted in the said member to lie in the plane 50 of constriction, a turbine arranged within the said member for driving the said propeller, and a stationary guiding member supported by the said member and having guiding wings inclined to guide in a direction 55 oppositely to the revolving direction of the said propeller, substantially as and for the purpose set forth.

60 2. A ship's smoke stack, comprising a substantially cylindrical funnel, a double conical insert in and connected with the said

funnel to form a constricted passage therein, the diameter of said passage being substantially less than that of said funnel, a stream-line member in the said funnel located underneath the point of constriction 70 and exhibiting even, eddy-preventing guide surfaces, a propeller mounted in the said member to lie in the plane of constriction, a turbine arranged within the said member for operating the said propeller, a stationary 75 guiding member supported by the said member and having guiding wings inclined to guide in a direction oppositely to the revolving direction of the said propeller, and an aperture closed by a door, both in the 80 biconical insert and in the funnel, substantially as and for the purpose set forth.

3. Induced draft device for smoke stacks, comprising in combination a substantially cylindrical funnel, a double conical insert 85 in and connected with the funnel to form a constricted passage therein, the diameter of said passage being substantially less than that of said funnel, a stream-line member in said funnel mounted underneath the point 90 of constriction, a screw-fan of substantially the same diameter as said constricted passage carried by said stream-line member to lie in the plane of constriction and a turbine mounted within said stream-line member 95 for driving said screw-fan with high velocity substantially as and for the purpose set forth.

4. Induced draft device for smoke stacks, comprising in combination a substantially cylindrical funnel, a double conical insert in and connected with the funnel to form a constricted passage therein, the diameter of said passage being substantially less than that of said funnel, a stream-line member in said funnel mounted underneath the point of constriction, a screw-fan of substantially the same diameter as said constricted passage carried by said stream-line member to lie in the plane of constriction; a turbine 100 mounted within said stream-line member for driving said screw-fan with high velocity and a stationary guiding member supported by said stream-line member and having guiding wings inclined to guide in a direction 105 oppositely to the revolving direction of said screw-fan substantially as and for the purpose set forth.

5. Induced draft device for smoke stacks, comprising in combination a substantially cylindrical funnel, a double conical insert in and connected with the funnel to form a constricted passage therein, the diameter of said passage being substantially less than that of said funnel, a stream-line member in said 115 funnel mounted underneath the point of constriction, a screw-fan of substantially the same diameter as said constricted passage carried by said stream-line member to lie in the plane of constriction, a turbine 120

125

mounted within said stream-line member for driving said screw-fan with high velocity, a stationary guiding member supported by said stream-line member and having guiding wings inclined to guide in a direction oppositely to the revolving direction of said screw-fan the adjacent walls of the funnel

and conical insert being each provided with apertures and doors for closing each of the apertures, substantially as and for the purpose set forth. ¹⁰

In testimony whereof I have signed my name to this specification.

HANS HASS.
